(57) CLAIM

The ornamental design for a strap pocket cover, as shown and described.

DESCRIPTION

FIG. 1 is a perspective view of the strap pocket cover showing my new design;

FIG. 2 is a top view thereof;

FIG. 3 is a bottom view thereof;

FIG. 4 is a left side view thereof;

FIG. 5 is a right side view thereof;

FIG. 6 is a front end view thereof;

FIG. 7 is a rear end view thereof; and,

FIG. 8 is a perspective front view showing the strap pocket cover covering a strap with the strap and advertising indicia shown in phantom lines.

The broken lines showing the strap and advertising indicia are for illustrative purposes only and form no part of the claimed design.
